UNITED STATES PATENT OFFICE.

WILLIAM F. GROVES, OF MARIETTA, GEORGIA.

COTTON-GIN HOUSE.

SPECIFICATION forming part of Letters Patent No. 296,687, dated April 8, 1884.

Application filed February 23, 1884. (No model.)

To all whom it may concern:

Be it known that I, WILLIAM F. GROVES, a citizen of the United States, residing at Marietta, in the county of Cobb and State of Georgia, have invented certain new and useful Improvements in Cotton-Gin Houses, of which the following is a specification, reference being had therein to the accompanying drawing.

This invention relates to gin-houses for cotton; and the object I have in view is to provide a house which will be fire-proof, and adapted to contain a gin and press, if so desired, and having connected therewith a tramway and tram for supplying cotton to the gin from an adjacent building, as will be herein-after more particularly set forth.

The accompanying drawing, which makes a part of this specification, is a longitudinal vertical section, in which—

20 A represents the house, the frame of which consists of a suitable number of vertical and horizontal scantlings framed together at proper intervals in a strong and durable manner. This house is provided with three or more 25 doors, D D and F. The frame (as well as the doors) is lined with sheet metal, and is provided with a sheet-metal top, E, in order to make it fire-proof. The cotton-gin and also a cotton-press are located in this house.

30 The press, however, may be located elsewhere, if desirable. The power for driving the gin is located outside of the house, and a shaft, l, runs from said power into the house for that purpose, and to operate such other mechanism as may be necessary.

35 m represents a shaft located near the top of the house, and which runs parallel with the shaft l.

40 L represents a pulley on shaft l', and k a pulley on the shaft m'. A band, J, passes around these two pulleys. Upon shaft m is a wind-

lass, k', around which a rope or chain, a, of suitable length, is passed. One end of this rope is connected to the windlass and the other to a tram or car, I.

45 G represents a tramway, which leads from the house where the crude cotton is stored to the gin-house. The tram I runs upon this way and conveys the cotton up and through the upper door, F. The cotton is dumped 50 from this tram, as seen, the fore wheels of the tram passing over and beyond the end of the way, so that its forward end drops to such an angle or position as will allow the cotton to pass from it. The windlass lifts the forward 55 end to the tramway again. A clutch and loose pulley are used upon the shaft m, to allow the tram to descend and then to draw it up again.

Having thus fully described my invention, 60 what I claim as new, and desire to secure by Letters Patent, is—

1. A gin-house frame constructed substantially as described, lined with sheet metal, and having metal doors and metal top to make the 65 same fire-proof, in combination with a tramway both within and without the house, and passing through one of the doors of the same, and adapted to carry a car operated by mechanism within the said gin-house, substantially 70 as described.

2. Windlass k', located within the gin-house, and provided with a cord or chain, a, in combination with the tram I and its way G, constructed and operating substantially as and 75 for the purpose set forth.

In testimony whereof I affix my signature in presence of two witnesses.

WILLIAM F. GROVES.
